UNITED STATES PATENT OFFICE

161,553

RADIO CABINET OR THE LIKE

Irving Strauss, Bridgeport, Conn.

Application December 19, 1947, Serial No. 143,241

Term of patent 7 years

(Cl. D56—4)

To all whom it may concern:

Be it known that I, Irving Strauss, a citizen of the United States, residing at Bridgeport, county of Fairfield, and State of Connecticut, have invented a new, original, and ornamental Design for a Radio Cabinet or the like of which the following is a specification, reference being had to the accompanying drawing, forming part thereof.

Figure 1 is a top view of a radio cabinet or the like, showing my new design.

Fig. 2 is a side view of the same.

I claim:

The ornamental design for a radio cabinet or the like, as shown.

IRVING STRAUSS.
